Inventor:

MARTIN DODGE,

By *Monroe Miller*

Attorney.

UNITED STATES PATENT OFFICE.

MARTIN DODGE, OF WASHINGTON, DISTRICT OF COLUMBIA.

WATER-HEATING FIREPLACE GRATE.

Application filed August 27, 1924. Serial No. 734,508.

To all whom it may concern:

Be it known that I, MARTIN DODGE, a citizen of the United States, residing at Washington, District of Columbia, have invented 5 certain new and useful Improvements in Water-Heating Fireplace Grates, of which the following is a specification, reference being had therein to the accompanying drawing.

10 The present invention relates to basket grates for use in fireplaces or hearths, and aims to provide a novel and improved basket grate through which water can flow to be heated so as to heat a radiator to 15 which the grate is connected.

Another object is the provision of a water receptacle on the radiator and connected to the hot water flow pipe between the grate and radiator to keep the radiator and channel of the grate full of water, and for the 20 further purpose of humidifying the air in the room and affording a supply of hot water.

With the foregoing and other objects in 25 view, which will be apparent as the description proceeds, the invention resides in the construction and arrangement of parts, as hereinafter described and claimed, it being understood that changes can be made within 30 the scope of what is claimed, without departing from the spirit of the invention.

The invention is illustrated in the accompanying drawings, wherein—

Figure 1 is a front view showing the improved grate in a fireplace and connected with the radiator.

Fig. 2 is a perspective view of the improved grate.

Fig. 3 is a perspective view of the stand 40 which supports the bottom of the grate.

Fig. 4 is a plan view of the bottom and stand of the grate, with the walls of the grate omitted.

The grate, including its stand, is composed of piping, and may be of different sizes. The grate is of rectangular form as shown.

The stand (shown by itself in Fig. 3) comprises the pipe sections 10, 11, 12 and 13 50 which are connected, excepting between the pipe sections 10 and 13, by elbows 14 and 14', thus connecting said pipe sections in series. The elbows have three branches including depending branches into which supporting legs 15 are secured. Said legs may

be of pipe sections, with caps 16 secured on the lower ends thereof to close said legs and form feet to set on the bottom of the fireplace or hearth. The elbow 14' is offset between the pipe sections 12 and 13 to bring 60 the pipe section 13 substantially horizontal slightly above the horizontal plane of the pipe sections 10, 11 and 12. The forward end of the pipe section 10 is connected by an elbow 17 with the upper end of a vertical 65 pipe section 18 which forms the fourth leg of the stand, and said pipe section 18 can extend down through the floor, as seen in Fig. 1. The pipe section 18 provides the cold water inlet for the grate.

The bottom of the grate comprises a zig-zag coil composed of the parallel pipe sections 19 which, as shown, are arranged parallel with one another and with the front and rear pipe sections 13 and 11, respectively, of the stand. Elbows 20 are used for connecting the ends of the pipe section 19 so that said pipe sections are connected in series, and the corresponding end of the foremost pipe section 19 is similarly connected by elbows 20 with the pipe section 13. The elbows 20 are used in preference to U-couplings, in order to space the pipe sections 19 apart sufficiently so that the ashes can pass down through the bottom of 80 the grate without clogging the slots between the pipe sections 19. The elbows 20 rest on the pipe sections 10 and 12 of the stand, so that the bottom of the grate is supported in a substantial manner by the 85 stand.

The walls of the grate constitute a rectangular coil, and each wall is composed of vertically spaced pipe sections 21. Said pipe sections of the adjacent walls are connected by elbows 22, to connect the pipe sections 21 in series, and the lower pipe section 21 of the rear wall is connected by elbows 24 with the rearmost pipe section 19 of the bottom, so that the water flows from 100 the bottom into the pipes of the walls of the grate. The elbows 22 are formed with enlargements or balls 23 that are seated on one another in superposed arrangement, in order to space the pipe sections 21 apart a 105 desired amount. This provides slots between the pipe sections 21 of sufficient width to enable a poker to be inserted through said slots for agitating the coal or wood in the grate and also to facilitate the discharge of 110

ashes and clinkers from the grate. The lower pipe sections 21 and elbows 22 are supported on the bottom of the grate.

A hot water flow pipe 25 is connected by an elbow 26 with the last pipe section 21 of the series, preferably above one rear corner of the grate, and leads upwardly to the upper portion of a suitable radiator 27. A cold water return pipe 28 leads from the lower portion of the radiator to the hollow leg or pipe section 18 of the stand.

The pipe sections 10, 11, 12 and 13, which form the frame of the stand, are connected in series with the pipe sections 19 of the bottom coil of the grate and the pipe sections 21 of the side wall coil, so that the flow of water through the frame of the stand, grate bottom and side walls of the grate is upwardly from the pipe 28 to the pipe 25.

This provides for the thermal-siphonic flow of water through the grate and radiator, inasmuch as the water when heated in passing through the conduit or channel of the grate will flow upwardly to the radiator, while the water in cooling in the radiator will flow downwardly through the pipe 28 back to the grate. This provides for an automatic circuitous flow of water through the grate and radiator.

The grate may be used for solid fuel, such as wood and coal, and may also be used for liquid and gaseous fuel by providing a suitable burner therein or thereunder, and the grate might also be used in connection with an electrical heater.

A tank or receptacle 29 is seated on the radiator and has a lower drain pipe 30 connected to the pipe 25, such as by means of a T-coupling 31. Water can be poured into the tank 29 from time to time, to keep the tank filled, and this will keep the radiator 27 filled with water. Furthermore, the tank

being seated on the radiator will be heated so as to heat the water therein. This is of advantage in order to humidify the air in the room, as well as to afford a supply of hot water. The water can be taken from the tank 29 when hot water is wanted.

Having thus described the invention, what is claimed as new is:—

1. A water-heating basket grate comprising a stand having a cold water inlet and a water passage leading from said inlet, a bottom coil resting on the stand and connected with the stand for the upward flow of the water from said passage through the bottom coil, and a side wall coil resting on the bottom coil and having an upper hot water outlet, said side wall coil having a lower connection with the bottom coil for the upward flow of water from the bottom coil through the side wall coil. 55

2. A water-heating basket grate comprising a stand having a frame and supporting legs, said frame having a water passage with a cold water inlet, a zig-zag bottom coil resting on said frame and connected at one end with said frame for the upward flow of water from said passage through the bottom coil, and a side wall coil resting on the bottom coil and having a hot water outlet 75 at its upper end, the lower end of the side wall coil being connected to the other end of the bottom coil for the upward flow of water from the bottom coil through the side wall coil, the bottom coil being composed of pipe sections and elbows connecting them and seated on the frame, and the side wall coil being composed of vertically spaced pipe sections connected by elbows seated one on the other. 80

In testimony whereof I hereunto affix my signature.

MARTIN DODGE.
